UNITED STATES PATENT OFFICE.

CHARLES BOCK, OF CHICAGO, ILLINOIS, ASSIGNOR TO ANDREW HOFFMAN, OF CHICAGO, ILLINOIS.

SPRING HINGE.

1,425,939.

Specification of Letters Patent. Patented Aug. 15, 1922.

Application filed August 6, 1918, Serial No. 248,600. Renewed October 15, 1920. Serial No. 417,268.

To all whom it may concern:

Be it known that I, CHARLES BOCK, a citizen of the United States, residing at Chicago, in the county of Cook and State 5 of Illinois, have invented new and useful Improvements in Spring Hinges, of which the following is a specification.

This invention relates to spring hinges applicable to swinging doors, and its object 10 is to provide a novel and improved hinge of this kind which is simple in construction, and which also holds the door open after fully swung in either direction.

The object stated is attained by means 15 of a combination and arrangement of parts to be hereinafter described and claimed, and in order that the same may be better understood, reference is had to the accompanying drawing forming a part of this specification.

In the drawing,

Figure 1 is a vertical section of the hinge; Fig. 2 is a horizontal section on the line 2—2 of Figure 1; and

25 Fig. 3 is an elevation of a hinge pin and a spring associated therewith.

Referring specifically to the drawing, the frame of the hinge is composed of two L-shaped pieces of strap iron which are riveted or otherwise rigidly connected to form 30 an open rectangular frame having a top 5, a bottom 6, a front side 7 and a rear side 8. This frame is set in a hole made in the corner of the door 9, and it is covered by a 35 U-shaped plate 10 placed to extend over the front wall 7, and the open inner and outer sides of the frame. Screws or other suitable fasteners 11 secure this assembly of parts in the hole made in the door.

40 A hinge rod or pin 12 extends between the top 5 and the bottom 6 of the frame, its lower end having a reduced portion 13 stepped in a hole in the part 6. The upper end of the pin extends through a hole in 45 the part 5 and projects upwardly a sufficient distance therefrom, to enter the top 14 of the door frame, said projecting portion being angular as shown at 12^a so that the pin cannot turn, and also passing 50 through a hole in a plate 15 mounted on the under side of the part 14. The rod 12 therefore acts as a pivot about which the door 9, with the hinge frame attached thereto, swings.

55 The hinge pin 12 is encircled by a coiled

spring 16 having its ends fashioned into hooks 17 and 18, respectively. The top hook 17 slips over an abutment 19 in the shape of an angle piece fastened to the top of the frame part 7; and the bottom hook 60 18 slips over a similar abutment 20 fastened to the bottom of the frame part 8. The two hooked ends of the springs are on diametrically opposite sides of the pin 12, and the latter also carries laterally outstanding fingers 21 and 22 over which the spring ends pass. Thus, it will be seen that swinging the door 9 in either direction winds the spring 16, so that when the door is released, the tension of the spring causes 70 the door to swing to closed position.

When the door 9 is swung in one direction the spring 16 is wound by the engagement of the top abutment 19 with the top hooked end 17 of the spring, and the lower hooked 75 end 18 of the spring is held stationary by the finger 21, the lower abutment 20 now swinging away from the latter end of the spring. When the door is swung in the opposite direction, the lower abutment 20 winds the 80 spring, and the upper finger 22 holds it stationary. The hooked ends of the springs therefore have a dual function, i. e., to be engaged by the abutments and to abut against the fingers extending outward from 85 the hinge pin 12.

The ends of the bottom finger 21 project from diametrically opposite sides of the pin 12 and the end 21^a extends into the path of a resilient latch member composed of a pair 90 of curved opposite spring fingers 23 secured to the frame part 7, so that the free ends 24 of said springs bear against the projecting end 21^a of the finger when the door approaches the open position, one of the spring ends coming into operation when the door is swung in one direction, and the other spring end when the door is swung in the other direction. As the limit of the swing is reached, the spring rides over the 100 finger 21^a and locks the door against swinging closed. The door will therefore remain wide open until manually swung to effect a release of the spring latch 23 from the finger end 21^a, whereupon the spring 16 105 completes the swing of the door to closed position. It will, of course, be understood that the tension of the spring 23 must be sufficient to hold the door against the tension of the hinge spring 16. The end of 110

the finger 21 which engages the spring 16 is shorter than the end 21^a so that it will not be stopped by the spring ends 24.

If the door should not close exactly in 5 its frame and should remain slightly ajar one way or the other, one or the other of the abutments 19 and 20 can be loosened and swung slightly one way or the other to offer more or less resistance to the spring, and 10 then tightened again.

The hinge structure is very simple and inexpensive in construction, it can be easily applied, and it effectually serves the purpose for which it is designed.

15 I claim:

1. A spring hinge for doors, comprising a hinge pin, a supporting frame carrying said pin, a spring coiled around the pin and anchored at its ends to the frame, a finger 20 extending laterally from the pin, and a resilient latch member carried by the frame and engageable by the finger when the door is open to so hold the same.

2. A spring hinge for doors, comprising 25 a hinge pin, a supporting frame carrying said pin, a spring coiled around the pin and having projecting end portions, abutments on the frame engaging said end portions of the springs, abutments on the pin also engaging the end portions of the springs, one pair of the aforementioned abutments being movable for tensioning the spring, and the other pair of abutments holding the spring ends stationary, one end being held while 30 the other end is being wound by the first mentioned pair of abutments, and a resilient latch member carried by the frame and engageable by one of the pin abutments when the door is open to so hold the same.

3. A spring hinge for doors comprising 35 a frame, a hinge pin journaled in the frame and having one end projecting beyond the frame and formed for interlocking engagement with a lintel plate or the like, a spring 40 coiled about the pin within the frame and having hook-like terminals oppositely opening in an unwinding direction, studs projecting from the frame into engagement with the spring terminals, and fingers projecting from the hinge pin into engagement 45 with the spring terminals.

4. A mortise spring hinge for doors comprising a shallow open sided frame, a hinge pin journaled adjacent its ends in the frame 55 and having one end projecting beyond the frame and formed for interlocking engagement with a lintel plate or the like, a spring coiled about the pin within the frame and having hook-like terminals oppositely opening 60 in an unwinding direction, studs projecting from the frame into engagement with the spring terminals, and fingers projecting from the hinge pin in a plane parallel to and closely adjacent to the studs 65 for engagement with the spring terminals.

5. A spring hinge for doors comprising a frame, a hinge pin journaled in the frame and having one end projecting beyond the frame and formed for interlocking engagement with a lintel plate or the like, a spring 70 coiled about the pin within the frame and having hook-like terminals oppositely opening in an unwinding direction, studs projecting from the frame into engagement with the spring terminals, fingers projecting from the hinge pin into engagement with the spring terminals, and a resilient latch member carried by the frame and engageable by the finger when the door is open to so hold the same. 75

6. A mortise spring hinge for doors comprising a shallow frame, a hinge pin journaled adjacent its ends in the frame and having one end projecting beyond the frame and formed for interlocking engagement 85 with a lintel plate or the like, a spring coiled about the pin within the frame and having hook-like terminals oppositely opening in an unwinding direction, studs projecting from the frame into engagement with the spring terminals, fingers projecting from the hinge pin in a plane parallel to and closely adjacent the studs for engagement with the spring terminals, and a resilient bifurcated latch member carried by the frame and 90 embracing the pin, the arms of the latch member engageable by oppositely disposed fingers when the door is open to hold the same 95 when swung in either direction.

7. A mortise spring hinge for doors comprising a shallow frame adapted to be housed in one corner of the door, a hinge pin journaled adjacent its ends in the frame and having a securing portion projecting beyond the frame and the door end, a lintel 105 plate having an aperture for accommodating the securing portion of the pin, a spring loosely coiled about the pin within the frame and having hook-like terminals oppositely opening in an unwinding direction, studs projecting from the frame into engagement with the spring terminals, fingers projecting from the hinge pin in a plane parallel to and closely adjacent the studs 110 for engagement with the spring terminals. 115

8. A mortise spring hinge for doors comprising a shallow frame adapted to be housed in one corner of the door, a hinge pin journaled at its ends in the frame and having one end projecting beyond the frame 120 and the door end and terminating in a securing portion, a lintel plate having an aperture for accommodating the securing portion of the pin, a spring loosely coiled about the pin within the frame and having hooklike terminals oppositely opening in an unwinding direction, studs projecting from the frame into engagement with the spring terminals, fingers projecting from the hinge pin in a plane parallel to and 125 closely adjacent to the studs for engagement with the spring terminals. 130

closely adjacent the studs for engagement with the spring terminals, and a resilient bifurcated latch member carried by the frame and embracing the pin in the plane 5 of one of the fingers whereby to frictionally engage the finger to hold the door open in either direction of its swing.

9. A spring hinge for doors comprising a frame, a hinge pin journalled in the frame 10 and having one end projecting beyond the same and formed for interlocking engage-

ment with a lintel plate or the like, a spring coiled about the pin within the frame and having a hook-like terminal opening in an unwinding direction, a stud projecting from 15 the frame for engagement with the spring terminal and a finger projecting from the hinge pin for engagement with the spring terminal.

In testimony whereof I affix my signature. 20

CHARLES BOCK.
